UNITED STATES PATENT OFFICE.

CHARLES E. LILLEY, OF BLUEFIELD, WEST VIRGINIA, ASSIGNOR TO WESTINGHOUSE ELECTRIC AND MANUFACTURING COMPANY, A CORPORATION OF PENNSYLVANIA.

LOCOMOTIVE SIDE FRAME.

1,039,691.

Specification of Letters Patent. Patented Jan. 13, 1914.

Application filed May 23, 1913. Serial No. 769,250.

To all whom it may concern:

Be it known that I, CHARLES E. LILLEY, a citizen of the United States, and a resident of Bluefield, in the county of Mercer and State of West Virginia, have invented a new and useful Improvement in Locomotive Side Frames, of which the following is a specification.

My invention relates to electric locomotives and similar vehicles, and it has special reference to side-frame castings for locomotives of the mining or industrial type.

The object of my invention is to provide a locomotive side-frame casting which shall be simple and inexpensive in construction and shall be adapted for use with either inside or outside hung motors, or with motors hung in tandem.

In Patent No. 1,039,691 granted to the Westinghouse Electric & Manufacturing Company upon an application filed by Graham Bright, a locomotive side frame of somewhat similar construction is disclosed having a plurality of integral binder members which may be selectively cut away to provide openings to receive the axle bearings of the driving motors, but in these side frames, although the wheel base may be varied in accordance with the types of motor-hangings which are employed, the steps in the changes of wheel base are relatively large by reason of the spacing of the pedestal members and, moreover, the minimum wheel base that may be obtained with inside hung motors is excessive for many operating conditions.

It is the purpose of my present invention to provide a locomotive side frame which may be adapted readily to various types of motor-hangings, the wheel base of which may be varied by relatively small steps, whereby the former length of side frame may be materially reduced and the minimum wheel base for inside hung motors may be greatly shortened. Thus, lighter and more inexpensive side frames result, and the frames may be adapted for a variety of service conditions.

Figure 1 of the accompanying drawing is a view in side elevation of a locomotive side frame constructed in accordance with my invention, portions of which may be cut away selectively to adapt it for any desired type of motor-hanging or wheel base. Fig.

adapted for inside hung motors; Fig. 3 is a similar view of a side frame adapted for tandem-hung motors and Fig. 4 is a view similar to Figs. 2 and 3 adapted for outside-hung motors, the motors and wheels being shown in dotted lines in the last three figures.

Referring to the drawing, the locomotive side frame shown comprises a centrally located longitudinal beam or girder 1, an upper parallel beam or girder 2 which is supported and trussed by means of a plurality of vertical bars 3, a lower beam or girder 4 disposed parallel to the girders 1 and 2 and embodying a plurality of binder sections 5, 6, 7, 8, 9 and 10 which are supported and rigidly associated with the central girder 1 by means of pedestal sections 11 to 18, inclusive. End portions 19 and 20 also constitute parts of the frame, in accordance with the usual practice.

It will be noted that the frame is provided with a plurality of pedestal sections 11 to 14 and 15 to 18, which are symmetrically disposed on each side of the frame and are severally spaced, the one from the other, by openings 21 of substantially half the width of an axle bearing 22, so that any pedestal section 11 to 18, together with its immediate adjacent binder portions 5 to 10 may be cut away to provide an opening of a size adapted to receive an axle bearing 22.

In Fig. 2, pedestal sections 12 and 17 together with binder portions 5, 6, 9 and 10 are cut away to accommodate the frame to a plurality of inside-hung motors 23, shown in dotted lines. Removable pedestal binders 24 are employed in the usual manner to permit the removal of axle bearings 22 and assist in strengthening the side frames.

In Fig. 3, pedestal section 12 and adjacent binder portions 5 and 6 and also pedestal section 16 and binder portions 8 and 9 are cut away to accommodate a pair of motors 25 hung in tandem, and in Fig. 4, outside-hung motors 26 are employed, the pedestal sections 13 and 16 with their adjacent binder portions 6, 7, 8 and 9 being removed.

By reason of the peculiar construction and arrangement of pedestal sections 11 to 18, it is clear that a variety of wheel bases may be obtained to accommodate any type of motor-hanging that is desired, and that the wheel base may be varied by relatively short steps which are substantially equal to half the width of the axle bearings, or half

the variation that may be secured by means of the structure shown in the patent hereinbefore mentioned. Moreover, the minimum wheel base for inside-hung motors is 5 less, by the full width of the axle bearing, than is possible with other side frames of this general type.

I do not wish to be restricted to the specific arrangement and location of parts 10 herein shown, as certain modifications may be made therein without departing from the spirit and scope of my invention.

I claim as my invention:

- 15 1. A locomotive side frame having symmetrically disposed openings on each side of the center provided with a plurality of pedestal sections, any one of which may be selectively removed to receive an axle bearing.
- 20 2. A locomotive side frame having a plurality of symmetrically disposed openings, any two of which are adapted to receive an axle bearing when the intermediate portion and adjacent lower portions of the frame 25 are removed.
3. A locomotive side frame having a plurality of pedestal sections joined at their lower ends, any one of which together with the immediate adjacent lower portions may 30 be selectively cut away to receive axle bear-

ings for two inside-hung, outside-hung, or tandem-hung motors.

4. A locomotive side frame having a plurality of pedestal sections joined at their lower ends and spaced apart to provide a 35 plurality of openings of substantially half the width of an axle bearing, any one of said pedestal sections being adapted to be cut away, in accordance with the type of motor-hanging desired, to provide an opening to receive an axle bearing.

5. A locomotive side frame adapted for various types of motor-hangings, and having symmetrically disposed pedestal sections connected at their lower portions by binder 45 sections spaced apart to provide openings substantially half the width of an axle bearing, the pedestal sections being adapted to be selectively cut away to receive axle bearings, whereby any one of a variety of wheel 50 bases may be secured which differ in length by substantially half the width of an axle bearing.

In testimony whereof, I have hereunto subscribed my name this 17 day of May 55 1913.

CHAS. E. LILLEY.
